UNITED STATES PATENT OFFICE.

FREDERICK M. RAMSDELL, OF WORCESTER, MASSACHUSETTS.

WIRE-COILING DEVICE.

1,417,629.

Specification of Letters Patent. Patented May 30, 1922.

Application filed April 15, 1920. Serial No. 374,081.

To all whom it may concern:

Be it known that I, FREDERICK M. RAMSDELL, a citizen of the United States, residing at Worcester, in the county of Worcester and State of Massachusetts, have invented a new and useful Wire-Coiling Device, of which the following is a specification.

This invention relates to a device for coiling wire, capable of general use but particularly adapted for the making of springs.

The principal objects of the invention are to provide a simple device for this purpose which can be operated by hand with no other apparatus except a vise or the like or which can be placed in a lathe and operated by that if desired. More specifically, the invention involves the combination with an arbor, on which the spring or coil is to be wound, with a coiling tool and a hand tool for operating the coiling tool itself; and an improved form of coiling tool adjustable to control the pitch of the coil.

Reference is to be had to the accompanying drawings, in which

Fig. 1 is a plan of a spring coiling device constructed in accordance with this invention;

Fig. 2 is a side view;

Fig. 3 is an edge view of the wire coiling tool removed from its support;

Fig. 4 is a bottom plan view of the same;

Fig. 5 is a plan of one of the removable elements for adjusting the spread of the spring coils;

Fig. 6 is an edge view of the same;

Fig. 7 is an edge view of another plate constituting part of the tool, and

Fig. 8 is a view showing the operation with all parts of the tool except the guiding discs omitted.

This invention is designed for use in small shops and in other places where much machinery is not available and for use on small jobs where only one or a few springs of the same size and character may be required. The device can be used in connection with a lathe for turning the arbor, the hand tool being held stationary as far as rotation is concerned, but I have shown it herein as being used in connection with a vise V which holds the arbor A in stationary position. It is necessary, therefore, to rotate the coiling tool and this can be done by hand in a very simple manner.

I have shown a tool holder which involves two parts or clamping members 10

and 11, these are provided with parallel perforations located at equal distances from the center and on opposite sides of the center. One of the perforations in each one 60 has a screw thread for receiving the screw thread of a handle 12. The screw threaded portion is of reduced diameter as will be obvious, leaving a shoulder for abutting against the outer surface of the member 10 65 or 11. Therefore by turning the two handles the two clamping members 10 and 11 can be moved toward and from each other and clamped. These two handles are knurled to permit of their being used in this 70 way and they project in opposite directions, but at a distance apart, from the opposite sides of the tool holder itself as shown more clearly in Fig. 1. These handles are used to clamp the device in position so as to hold the tool that is to be used and also to hold a centering and guiding disc 14 in a cylindrical recess at one end of the tool holder. The other end of the tool holder also has a similar recess which is adapted for receiving 75 a projection 20 or element of a similar shape connected with the wire coiling tool itself. The tool holder as I have called it, is therefore, in the form of a wrench which can be used for several purposes.

The coiling tool comprises a plate 21 which carries the projection 20 that fits in the tool holder and is held clamped therein when the tool holder is tightened up. This plate is provided with a screw threaded 90 opening 22 for receiving a screw 23. On this plate and fastened down to the same by this screw is a thrust plate 24 through which it passes. The plate 21 is provided with a fixed pin 25 which also passes through this 95 plate 24.

I have shown in addition to the plate 24 a series of spacing plates 26, each one with a so-called keyhole slot 27 in it, the larger part of which is for the reception of the screw 100 23 and the smaller part for the pin 25. These plates are set to produce any desired spacing. One or more of the plates 26 can be adjusted to register with the first plate 24 if desired, which ordinarily is of the thickness equal to 105 the diameter of the wire of maximum size. One or more of the plates 26 are set so that when the tool is in position on the arbor they will project over the end of the plate 24 substantially into contact with the arbor. 110 In the drawings I have shown three of these plates in use and two out of use. If the

spring is to be wound more finely only two of them are used, but if wound more coarsely, additional ones are to be added. In Fig. 1 I have shown two of these spacing plates 26 as set off at an angle merely to keep them where they will not be lost. These two plates are entirely idle and out of use in the position shown in Fig. 1, the other three being the ones that perform the work. 5
10 In use of the device the end of the wire W is passed through an open ended slot 30 extending centrally through the end of the arbor and from that up through the space 31 between the portion of the three plates 26. 15 This holds the end of the wire in positive position, and the operator simply turns the tool about the stationary arbor. The result of this is to gradually wind the wire on the arbor, the amount of space between the different coils being controlled by the number of plates 26 which are mounted in the position for substantially engaging the arbor. 20

This constitutes an extremely simple winding device which can be operated by hand and adjusted very conveniently to produce springs of any desired character within reasonable limits. It is easily set up so that it can be used for coiling a single spring if desired and the tool holder, as I have called it, 25 or hand tool, is capable of many other uses to hold other metal working tools if desired. 30

Although I have illustrated and described only a single form of the invention I am aware of the fact that modifications can be 35 made therein by any person skilled in the art without departing from the scope of the invention as expressed in the claims. Therefore I do not wish to be limited to all the details of construction herein shown and described, or to the particular form of hand 40 tool shown, but what I do claim is:—

1. As an article of manufacture, a hand tool for coiling springs comprising an arbor and a work holder rotatable thereto, a flat plate secured to said work holder, and a series of spacing plates adapted to be mounted on said plate in different planes and fixed thereto in two positions, those nearest the flat plate being spaced from the arbor, whereby 50 the coarseness of the coil produced can be changed by the fixing of the necessary number of said spacing plates in operative position.

2. The combination with a plate having a 55 centering device for an arbor and a projection by which it can be clamped for manipulation, a headed screw carried by said plate, a plate on the first named plate, a series of detachable spacing plates having keyhole slots 60 therein adapted to be mounted under the

head of said screw, and a guide on the first named plate for entering the narrow part of said keyhole slots to hold said spacing plates in position.

3. The combination of a clamping device 65 having a central recess in each end, said recesses being spaced from each other longitudinally, of a guide disc clamped in one of said recesses and having a perforation at the center for fitting an arbor on which it is to be used and centering the clamping device, a centrally perforated cylindrical projection adapted to fit in the other of said recesses and provided with a guide centrally located therein for fitting the surface of the arbor, a plate 75 connected with said projection for operation on the work, and wire coiling members detachably connected with said plate.

4. As an article of manufacture, a wire coiling tool comprising a complementary 80 pair of members, each having a clamping jaw on each end, a centrally perforated circular guide disc located in one pair of jaws, a circular projection located in the other, a pair of spaced oppositely projecting handles 85 for forcing said members together and clamping the jaws against the disc and projection, and a second centrally perforated guide disc carried centrally by said projection, said perforations through said discs 90 constituting means for centering and guiding the tool on an arbor, and means connected with said projection for holding a wire against the arbor as the tool is rotated thereon and spacing the coils apart as they are 95 formed on the arbor.

5. As an article of manufacture, a hand tool for coiling springs comprising an arbor and a work holder centered thereon and relatively rotatable, a flat plate secured to said 100 hand tool and provided with a guide pin and a fastening screw, and a series of spacing plates adapted to be mounted on said flat plate and having keyhole slots through which they are fixed thereto by the screw, 105 and through which said pin projects.

6. The combination with a plate having a centering device for an arbor and a projection by which it can be clamped for manipulation and a headed screw carried by said 110 plate, of a thrust plate on the first named plate and a series of detachable spacing plates having keyhole slots therein adapted to be mounted under the head of said screw, a guide on the first named plate for entering 115 the narrow part of said keyhole slots to hold said spacing plates in position.

In testimony whereof I have hereunto affixed my signature.

FREDERICK M. RAMSDELL.
